Primary Examiner — Michelle E. Wilson*Assistant Examiner* — Clese Moore, Jr.*(74) Attorney, Agent, or Firm* — Lee & Hayes, P.C.(57) **CLAIM**

The ornamental design for a vehicle toy, replica, and/or model, as shown and described.

DESCRIPTION

FIG. 1 is a top, front, right-side perspective view of a vehicle toy, replica, and/or model;

FIG. 2 is a front view thereof;

FIG. 3 is a back view thereof;

FIG. 4 is a left-side view thereof;

FIG. 5 is a right-side view thereof;

FIG. 6 is a top view thereof; and,

FIG. 7 is a bottom view thereof.

The dashed broken lines depict portions of the vehicle toy, replica, and/or model that form no part of the claimed design. The dot-dash broken lines in FIG. 7 depict a boundary and the region within the boundary forms no part of the claimed design.

1 Claim, 7 Drawing Sheets(56)
